UNITED STATES PATENT OFFICE.

JOHN R. BOWLER, OF NEW BRIGHTON, NEW YORK.

DETONATING DEVICE.

Application filed August 10, 1921. Serial No. 491,097.

To all whom it may concern:

Be it known that I, JOHN R. BOWLER, a citizen of the United States of America, residing at New Brighton, in the county of 5 Richmond and State of New York, have invented certain new and useful Improvements in Detonating Devices, of which the following is a full, clear, and exact description.

10 This invention relates to detonating devices adapted to be employed as an alarm, poaching gun, animal trap, etc., but more particularly designed to catch fish.

One of the principal objects of the invention is to provide a simple, though reliable, device of the class above mentioned. Other objects and advantages will be apparent as the invention is hereinafter disclosed.

Referring to the drawings which illustrate what I now consider a preferred form of the invention,

Fig. 1 is an edge elevation of a fish lure embodying the invention.

Fig. 2 is a side elevation thereof with one 25 of the casing sections removed and certain parts shown in section.

Figs. 3 and 4 are sections on the lines 3—3 and 4—4, respectively, of Fig. 2.

Fig. 5 is a detail side elevation of one 30 form of hook employed.

Fig. 6 is a detail elevation of a device adapted to be employed to cock the firing mechanism and to eject a used cartridge casing.

35 The physical embodiment of the invention which I have selected for the purpose of illustration comprises a two section casing comprising the similar parts 10 and 11. One of these parts is provided with dowel

40 pins 12, 13 while the other is provided with openings 14 adapted to receive the pins thereby to hold the two parts of the casing together. If desirable the ends of the pins 12, 13 may be upset after the parts are as-

45 sembed in order positively to secure the casing halves together. Except for the difference above noted the two members 10 and 11 may be exactly similar and a description of one will suffice for the other.

50 The casing is provided with a cartridge-

receiving device, contains firing mechanism and a detent for holding the latter in cocked position, and a hook and a securing device which, when pulled in relatively opposite directions, cause the detent to be released to 55 detonate the cartridge. The cartridge-receiving device is shown in the form of a block 15 provided with a cartridge-receiving bore 16 adapted to receive a cartridge 17.

The block 15 is pivoted to the casing at 12 so 60 as to be movable from a position, shown in dotted lines in Fig. 2, in which a used cartridge may readily be ejected by means of a suitable tool, such as the one illustrated

at 18 in Fig. 6, to the full line position in 65 which the cartridge is adapted to be detonated by means of the firing mechanism hereinafter more specifically disclosed. The block 15 may be detachably held in the last

mentioned position by means of a bail 19 70 (see Figs. 1, 2 and 4) pivoted in openings 20 provided in the casing parts 10, 11 and movable from a position in which it engages a shoulder 21 on the block 15 to a position permitting the latter to be swung to 75 its dotted line position.

The firing mechanism is shown in the form of a plunger 22 slidably mounted in a bore 25 provided one-half in section 10 and the other half in section 11. The plunger 80 is provided with a firing pin 23 adapted to pass through the reduced end of the bore 25 to engage and fire a cartridge 17. The opposite end of the plunger 22 is provided with a rod 24 surrounded by a compression spring 85 26 which seats at its opposite ends against the plunger and one end of the bore 25, serving to bias the plunger to cartridge-engaging position.

The detent is shown as a two arm device 90 30 pivoted at 31 within the casing, the two sections of the latter being cut away, as indicated at 32, to permit the detent to be moved from a position in which it holds the firing mechanism in cocked position 95 (shown in full lines in Fig. 2) to a position in which the plunger is permitted to pass under the action of spring 26 (see dotted line position of the detent in Fig. 2).

The casing is shown provided at the 100

cartridge end with a hook 40 and at its other end with a securing device shown in the form of a swivel 41 having an eye 42 to which a fishing line or other fastening device 5 vice may be secured. Various forms of mechanism may be employed to trip the detent 30 upon opposite relative pull of the members 40 and 41. Preferably the shank of the hook 40 is slidably mounted in a bore 10 43, provided in the casing 10, 11, and terminates in an eye 44 through which one arm of the detent 30 extends, the casing sections being slotted as indicated at 45 to accommodate movement of the eye portion 44.

15 The assembly of the device will be readily understood by those skilled in the art. The various parts are mounted as shown in Fig. 2 (except that no cartridge is to be in the block 15 at this time and the block 22 is 20 in position adjacent the cartridge end). The other casing section 11 is then placed in position over the section 10 and forced home on the pins 12, 13, 31. The ends of the latter may then be upset if desired.

25 To load and cock the device, a blank or other cartridge 17 is inserted into the block 15 after the latter has been moved to the dotted line position (see Fig. 2). The rod of the tool 18 may then be inserted into the 30 bore 25 through its upper end and the plunger moved to cocked position in which one arm of the detent 30 moves into the holding position (shown in full lines in Fig. 2) under the weight of the hook 40 or by virtue 35 of a push manually exerted upon the hook 40. The block 15 may then be swung to the full line position and detachably held there by moving the bail 19 over the shoulder 21.

40 If the device is to be employed to catch fish, and it is admirably adapted to such use, a line (not shown) is secured to the eye 42 and the device towed through the water. The device will spin on the swivel 41 and 45 as the casing 10, 11, is preferably made of aluminum or other suitable light, white metal or plated metal, it will present an attractive lure to the fish. When a fish strikes the hook 40 the pull upon the latter, 50 with respect to the element 41 and casing 10, 11, causes the detent 30 to be moved to the position shown in dotted lines in Fig. 2. The spring 26 then propels the plunger 22 to cause the pin 23 to engage 55 and fire the cartridge 17. Explosion of the cartridge 17, under water, stuns the fish making it easy to land, and the recoil of the casing 10, 11 causes the hook to penetrate the mouth of the fish effectively to 60 pale the latter. The firing of the cartridge serves also as an addition indication of a strike. The used cartridge may be ejected and the device reloaded and cocked with the aid of the tool 18 as will now be obvious.

65 If employed for fishing the cartridge 17

should of course be a water-proof one. If desirable the hook 40 may be baited in the usual manner.

It will be understood that the device is adaptable to uses other than as a fishing implement. For example, one of the members 40, 41 may be secured to a door or window and the other to the frame thereof, by means of suitable cords or wires, so that upon opening of the door or window the cartridge 17 will be fired. When so employed the device constitutes an effective burglar alarm. The device may be employed to destroy animals by suitably anchoring the device 41 and by baiting the hook 40, the device being preferably loaded with a ball or shot cartridge when so employed. Again, the device may be employed as a poaching gun or alarm. Other uses within the broader scope of the invention will occur to those skilled in the art.

The device is not only adaptable to various uses but is susceptible to modification in various respects without departing from the scope of the invention as outlined in the claims appended hereto. To avoid surplusage I have not illustrated these various modifications but have restricted the present disclosure to what I now consider a preferred physical embodiment of the invention.

It will be noted that the opposite ends of the bore 25 are provided with vents 60 to permit the escape of fluid and to prevent impedance of the movement of the plunger.

What I claim is—

1. A fish lure comprising in combination, a casing, a hook projecting from one end of said casing and slidably mounted therein, a cartridge holder pivoted to said casing 105 and movable from a position in which it may be loaded to a position in which it directs the fire of a cartridge toward said hook, means for holding said device in the last mentioned position, cartridge-firing 110 mechanism mounted within said casing, a detent for holding said firing mechanism in cocked position, means for releasing said detent when said hook is moved away from said casing, and a swivel mounted at the 115 end of said casing opposite said hook whereby a line may be secured to said casing.

2. The device as set forth in claim 1 in which the casing is constructed of two similar members.

3. A fishing lure comprising in combination, a casing, a hook projecting from one end of said casing, a cartridge holder connected to said casing to direct the fire of a cartridge toward said hook, a firing plunger 125 slidably mounted in said casing, said casing being provided with a discharge port to permit discharge of water upon movement of said plunger toward the cartridge, spring means biasing said plunger toward firing 130

position, line-securing means at the end of said casing opposite said hook, a detent within said casing for holding said plunger in cocked position, and means within said 5 casing for releasing said detent when said hook and securing means are moved relatively away from each other.

4. The device set forth in claim 3 in which

the hook is slidably mounted in the casing and in which the means for releasing the 10 detent comprises a connection between the hook and detent.

In testimony whereof I hereto affix my signature.

JOHN R. BOWLER.
